UNITED STATES PATENT OFFICE

2,499,328

APPARATUS FOR DRYING LAUNDRY

Sam Pawlansky, Chicago, Ill., now by judicial
change of name, Sam Women Sam

Application October 15, 1947, Serial No. 780,079

4 Claims. (Cl. 34—80)

1

In my co-pending application for laundry drying racks, for which Patent Number 2,481,443 was issued and for which an application for re-issue, Serial Number 133,901 was filed on December 19, 1949, I have disclosed a rack from which wet laundry may be suspended for the purpose of drying.

The present invention relates to the apparatus for drying laundry, and has for its main object the provision of an air tight sealed box within which a rack such as disclosed in my said co-pending application, or a rack of any other suitable construction, with wet laundry suspended thereon, may be received, with means associated with the said box for drying the laundry.

A still further object of the present invention is the provision of a box wherein wet laundry may be received, with means associated therewith for speeding the evaporation and adsorption of moisture from wet laundry.

Another object of the present invention is the provision of a hermetically sealed box, within which wet laundry may be received hanging on a rack with ample exposure of its surfaces to air, with means therein provided for circulating the air in the box and passing the water vapor-laden air through a dehumidifying, adsorptive desiccant and re-circulating the dehumidified air warmed by the heat of adsorption in order that the warm dehumidified air may sustain continued evaporation of the moisture of the laundry.

With the above general objects in view and others that will appear as the invention is better understood, the same consists in the novel construction, combination and arrangement of parts hereinafter more fully described and illustrated in the accompanying drawings and pointed out in the appended claims.

In the drawings forming a part of this application, and in which like designating characters refer to corresponding parts throughout the several views,

Fig. 1 is a front elevational view of one form of the present device, including a box with an air tight sealable door leading thereinto in an open position;

Fig. 2 is a longitudinal cross-sectional view of said form of the present device, on a vertical plane, the view having been taken on line 2—2 of Fig. 1;

Fig. 3 is a partly cross-sectional, and partly plan fragmentary view, on line 3—3 of Fig. 2;

Fig. 4 is a transverse, enlarged cross-sectional view through a pair of porous boxes of water vapor adsorbing desiccant through which the

2

water vapor-laden air is forced for adsorbing therefrom its water vapor which was evaporated from the laundry;

Fig. 5 is a front elevational view of the present device of a modified construction;

Fig. 6 is a cross-sectional view, on line 6—6 of Fig. 5; and

Fig. 7 is a cross-sectional view on line 7—7 of Fig. 6.

Referring to the present drawings in detail, there is shown therein a laundry drying rack, including four posts 10, one side pair of which is joined by brace 11 at their lower ends, and by brace 12 at their upper ends. The end pairs of said posts 10 are connected at their lower ends by braces 13. Each post 10 carries at its lower end caster 14, by means of which the rack may be rolled upon the floor.

Set within a pair of end posts 10, and rigidly connected thereto, is a plurality of bars 15, which are in a mutually spaced relation on a vertical plane. Each of said bars 15 is provided with a plurality of upwardly projecting lugs 16.

The opposite pair of end posts 10 is provided with a plurality of shafts 17, each shaft being on the plane with the corresponding bar 15. Set upon each of said shafts 17, in a mutually spaced relation, is a plurality of tape receiving housings 18, each containing a spring-actuated reel, upon which tape 19 is wound. The free end of each tape 19 is provided with ring 20 to be engaged by lug 16 when tape 19 is fully extended in the rack from its housing 18. When the free end of tape 19 is released, the spring actuated reel within housing 18 winds said tape 19 and retracts the same into the housing.

The construction of the rack hereinabove described is in all respects identical with that shown and described in my said co-pending application, and it is understood that in connection with the present invention a rack of any construction may be used.

The present invention includes a substantially rectangular box 21, supported upon casters 22. The vertical walls of said box 21 are upwardly extended above the roof thereof in order that in conjunction therewith they may define water receiving pan 23.

One of the end walls of said box 21 is provided with a door opening 24 closed by door 25. Said end wall along the marginal portion adjacent said opening 24 is provided with gasket 26. Similar gasket 27 is affixed on the inner face of door 25 and adjacent the marginal portion thereof. Two gaskets 26 and 27 are adapted to come in mutual

contact when door 25 is swung upon hinges 23 to a closed position to form an air tight seal.

Welded or otherwise affixed to the side walls of box 21 and in a spaced relation with the bottom wall thereof is ledge 29, which adjacent one end thereof is recessed as at 30, thereby defining a pair of tongues 31, each in contact with the adjacent side wall of box 21 as is seen in Fig. 3.

The bottom wall of box 21, the side walls thereof and said ledge 29 define air vent 32. One end of said air vent 32, adjacent said recess 30 is capped by a constricted hood 33, the mouth of which is fitted into air pump fixture 34, within which conventional air expelling blades are located, which are driven by electric motor 35, for expelling the air from air vent 32, through hood 33 and out of exhaust opening 36 of air pump fixture 34.

Ledge 29 terminates short of the adjacent end wall of box 21 and of door 25 permitting passage of air from box 21 into air vent 32. Otherwise said air vent 32, including said hood 33, is airtight.

Receivable within air vent 32, and fitting same tightly in a longitudinal relation therewith, is a plurality of packages 37, each made of substantially rectangular container 38 made of wire cloth or of any other suitable material. Each of said containers 38 receives comminuted and well packed desiccant, such as silica gel or any other suitable dehumidifying, hygroscopic, adsorptive desiccant. Each of said packages 37, adjacent one end thereof, may be provided with handle 39, whereby the package may be handled when inserted into or removed from said air vent 32. Attached to the wall of the adjacent package 37, at 40 is link member 41 of a resilient metallic material. Said link member 41 has a central bulging portion disposed away from package 37 with which the same is connected at 40. The ends of said link member 41 normally contact the wall of package 37 with which the same is connected, while the central bulging portion thereof is hooked with handle 39 of the adjacent package 37, in a transverse relation therewith, as is clearly seen in Fig. 4. As said packages 37 are inserted into vent 32 the same are hooked up in succession through the medium of said handles 39 and link members 41. As the outermost package 37 is pulled by its handle 39, all of said packages 37 are caused to shift out of said air vent 32 due to the connection of all of said packages through said handles 39 and link members 41. Another function of said link members 41 is to act as spacers between the several packages 37 and shock absorbers, preventing crushing or distortion of packages 37, which were liable to ensue as the same are shifted into vent 32.

Receivable within box 21 is the laundry drying rack hereinabove described. The same is adapted to rest by a pair of end posts 40 upon tongues 31, while the opposite pair of end posts 40 rests upon the end of ledge 29 adjacent door 25. Stops 42, affixed either to the adjacent vertical wall of box 21 or to tongues 31, prevents the rack from coming in contact with the adjacent end wall of box 21. The rack is insertable into box 21 through door opening 24, and to facilitate its rolling into box 21 incline 43, supported by its upper end upon ledge 29 and extended through door opening 24, may be provided, as is seen in Fig. 2. Of course, laundry to be dried is suspended upon tapes 19.

When the rack with laundry thereon is in position within box 21, door 25 is then shut and the drying apparatus is set in operation. On starting motor 35 air is sucked from air vent 32 and hood 33 into pump fixture 34, and expelled through its exhaust opening 36 into the space of box 21, above ledge 29, to circulate around the suspended laundry. As the air is drawn from air vent 32, and expelled through said air pump fixture 34, new supply of air from the box enters air vent 32 at the opposite end thereof through recess defined by door 25 and the adjacent end of ledge 29. As long as the air pump is in operation there is constant air circulation between air vent 32 and the upper portion of box 21, as is indicated by arrows in Figs. 2 and 6. The air forced through the air pump has the degree of moisture content reduced due to the adsorption thereof by the desiccant contained in packages 37. That air which has been forced to circulate around the laundry upon the rack receives the moisture thereof to be again passed through desiccant packages 37, to be again expelled through the air pump. This process continues until the laundry has become dry and its moisture transferred to the desiccant in packages 37 due to the air circulation aforesaid.

Pan 23 may be filled with water only for the purpose of reducing the temperature of newly reactivated hot desiccant in packages 37 and for bringing it to a room temperature immediately upon its leaving the oven so as not to deteriorate the rubber gaskets 26 and 27. This is accomplished by depositing packages 37 containing hot desiccant in vent 32, and closing door 25, with no laundry rack or laundry in box 21. Pump 34 is then set in operation and air within the apparatus is caused to circulate through vent 32 and box 21 as hereinabove described. The temperature of air coming in contact with the roof of box 21 is reduced due to the cool water in pan 23. This operation is continued until the desiccant has been cooled to a room temperature. When this has been effected, residual water if any is removed from pan 23 and the apparatus will then be in condition for normal use for drying the laundry.

All parts which are common to the preferred form of the invention, hereinabove described, and to the modified form thereof, illustrated in Figs. 5, 6 and 7, are marked with the same reference characters. In the said modified form of the invention box 21 is devoid of air vent 32 and ledge 29. There, the laundry drying rack rests directly upon the bottom wall of box 21. The end wall of box 21, with which door 25 cooperates, is provided with an upwardly directed extension 44, provided at its upper end with a circular opening, within which the adjacent end of cylinder 45 is tightly fitted. Said cylinder 45 is preferably made of metal of high degree of conductivity.

Affixed to the outer face of said extension 44, and in a concentric relation with cylinder 45 is a circular gasket 46. Closure 47 suspended upon extension 44 by hinge 48, carries similar gasket 49. When said closure 47 remains in a closed position, shown in Fig. 6, gaskets 46 and 49 contact and form an air tight seal. Latch 50 maintains said closure 47 in a closed position with relation to the open end of cylinder 45.

Said cylinder 45 is further supported on the roof of box 21, and in a longitudinal relation with said box, by means of a plurality of supporting members 51, which may be rigidly affixed to the roof of said box 21. The upper ends of said supporting members 51 have semi-circular re-

cesses within which said cylinder 45 is seated. The opposite end of said cylinder 45 terminates in a funnel-shaped member 52, the constricted mouth of which connects with pipe 53. Said pipe 53 extends through the roof of box 21 and passes downwardly into said box 21 and along the adjacent end wall of said box 21, and centrally thereof. The opposite end of said pipe 53 is connected to air pump 34 operable by motor 35, as in the preferred form of the invention. The air sucked through pipe 53 is directed in an upward direction into box 21, as indicated by arrows in Fig. 6, for causing the circulation thereof among the laundry pieces suspended on tapes 19 in the laundry drying rack which remains in an operative position within box 21, as seen in Figs. 5 and 6.

Air conduit 54 is extended into box 21, adjacent the opposite end thereof, and within a corner thereof defined by said end wall and one of the side walls of box 21. The open, lower end of said conduit 54 is disposed adjacent the bottom wall of box 21. Said conduit 54 is extended through the roof wall of box 21, and the upper end thereof is bent toward the longitudinal center of box 21, and is connected to cylinder 45 at the adjacent end of the latter.

Said cylinder 45 receives through its open end when closure 47 is opened, a plurality of packages 55, which are of like construction and contents as packages 37 used in connection with the preferred form of the invention hereinabove described, except that the former are of a cylindrical formation, snugly fitting within cylinder 45.

Handles 39 and link members 41, cooperating with said packages 55, are of like construction and operation as the corresponding parts employed in connection with packages 37.

The outermost package 55, which is adjacent to closure 47, is spaced away from the adjacent end of cylinder 45, in order not to obstruct the inlet mouth of conduit 54, as is seen in Fig. 6.

During the operation of the modified form of the apparatus, both door 25 and closure 47 should remain in closed positions.

During the operation of pump 34 the air is circulated and re-circulated through cylinder 45, pipe 53, box 21 and conduit 54 which altogether define an intercommunicating air tight system. Air leaving box 21 enters conduit 54 through the open, lower end of the latter and is forced into cylinder 45 due to the suction produced by air pump 34. In cylinder 45 the air laden with moisture extracted from the moist laundry upon the rack within box 21, filters through desiccant containing packages 55. The desiccant of course adsorbs water vapor from the air passing therethrough, so that the re-circulated air leaving pump 34 from pipe 53 is dehumidified, to act anew upon the laundry within box 21. This process of air circulation continues as long as pump 34 continues to operate.

Optionally cylinder 45 may be enclosed within a cloth sheath 56, which may be soaked with water, which due to its vaporization cools cylinder 45 and decreases the temperature of the contents thereof, including the desiccant within packages 55 and the air passing therethrough. Thus the exchange of the temperatures on the outside and on the inside of cylinder 45, and their equalization is effected. If however cylinder 45 is made of metal having a high degree of heat conductivity, such as aluminum for instance, or is provided with cooling fins formed on its

surface and if pipe 53, conduit 54, supports 51 and extension 44 are heat insulated and furthermore if means are provided to plug pipe 53 and conduit 54, so as to stop air communication between cylinder 45 and box 21, then sheath 56 may be dispensed with because then not enough heat would be transmitted from freshly reactivated hot silica gel in cylinder 45 to deteriorate quickly gaskets 26 and 27.

It is preferable to moisten sheath 56 only at the time when newly reactivated desiccant, still in a hot condition, has been placed in cylinder 45, in order to bring its temperature to a normal room temperature. Sheath 56 should not be moistened during normal operation while laundry undergoes the drying process.

When the desiccant in packages 37 and 55 has come to a saturation point, the same may be readily reactivated, without necessarily removing the same from containers 38.

When exposed desiccant is placed in box 21, vent 32 or cylinder 45 may be eliminated, because due to conventional air currents in box 21 the moisture-laden air will come directly in contact with the desiccant for having its moisture adsorbed thereby.

While there is described herein a preferred embodiment of the present invention, it is nevertheless to be understood that minor changes may be made therein without departing from the spirit and scope of the invention as claimed.

What I claim as new is:

1. An apparatus for drying laundry comprising an air-tight compartment means in said compartment adapted to receive suspended moist loose exposed laundry, a flue connected at opposite ends with the compartment means in said flue adapted to receive a dehumidifying agent, said means comprising a plurality of open-meshed containers, a handle on one end of each container, a link on the opposite end of each container inserted through the handle of an adjoining container whereby the several containers are interconnected and slidably inserted into and removable from the flue as a unit, and a fan for circulating air through said compartment and said flue.

2. An apparatus for drying laundry comprising an air-tight compartment having suspending means adapted to receive moist loose exposed laundry, a flue disposed outside of said compartment, means in said flue adapted to receive a quantity of dehumidifying material, said means comprising a plurality of open-mesh containers, a handle on one end of each container, a link on the opposite end of each container inserted through the handle of an adjoining container whereby the several containers are interconnected and slidably inserted into and removable from the flue as a unit, pipes connected to both ends of said flue and extending into said compartment, one of said pipes having an open end within said compartment extending below said laundry supporting means, and an air pump connected with the inner end of the other of said pipes being adapted to induce movement of air enclosed within said compartment in a continuous path through said compartment, said pipes and said flue, the air moving in said compartment around the laundry therewithin withdrawing moisture therefrom, the moisture-laden air moving into said flue through one of said pipes being acted upon by said dehumidifying material in said flue for reducing the moisture content thereof.

3. An apparatus for drying laundry comprising an air-tight compartment having a bottom and a door at one end thereof, a floor in said compartment spaced above said bottom and cooperating with the bottom to form a flue therebetween, said floor being spaced from said door at one end for air circulation therebetween, air circulating means connected to the opposite end of said flue, means in said flue adapted to receive a dehumidifying agent, said means comprising a plurality of open-mesh containers, a handle on one end of each container, a link on the opposite end of each container inserted through the handle of an adjoining container whereby the several containers are interconnected and inserted into and removable from the flue as a unit, and means in said compartment being adapted to receive suspended moist laundry.

4. An apparatus for drying material comprising a compartment adapted to receive the material to be dried, a flue communicating with said compartment, a plurality of foraminous containers enclosing a desiccant, a handle on one end of each of said containers, a link on the opposite end of each of said containers insertable through

and detachable from the handle of an adjacent container whereby the plurality of said containers are interconnectable and slidably insertable into and removable from said flue as a unit, and a fan for circulating air through said compartment and said flue.
